OVERLOAD RELEASE MECHANISM

Henry C. Nissen, Stratford, Conn., assignor to The
Singer Manufacturing Company, Elizabeth,
N. J., a corporation of New Jersey

Application January 10, 1946, Serial No. 640,196

9 Claims. (Cl. 112—220)

1

This invention relates to sewing machines and, more particularly, to sewing machines having a compound needle and lower feed-dog work-advancing mechanism, together with a rotary loop-taker of the lock-stitch type.

The present invention has for its primary object to obviate breakage of parts upon overload of the rotary loop-taker of a sewing machine having a compound needle and lower feed-dog work-advancing mechanism in which the feed-dog is operated from actuating mechanism disposed below the work-support of the machine.

More specifically, the present invention has for an object to provide for continuance of the synchronous, work feeding operation of the needle and lower feed-dog of a compound work-advancing mechanism in which the feed-dog is operated from actuating mechanism disposed below the work-support of a sewing machine, after release of the sewing machine loop-taker from its driving mechanism due to the action of the overload release mechanism.

Other and more specific objects of the invention will be apparent from the following description and claims.

The invention comprises the devices, combinations and arrangements of parts hereinafter described in connection with the accompanying drawings, which illustrate a preferred embodiment of the invention and in which:

Fig. 1 represents a vertical longitudinal section of a sewing machine containing the present improvements.

Fig. 2 represents a bottom plan view of the sewing machine.

Fig. 3 represents an enlarged transverse section taken substantially on the line 3—3 of Fig. 1.

Fig. 4 represents an enlarged transverse section taken substantially on the line 4—4 of Fig. 1.

Fig. 5 is a sectional view taken substantially on the line 5—5 of Fig. 3.

Fig. 6 represents an enlarged transverse section taken substantially on the line 6—6 of Fig. 1.

The sewing machine illustrated in the drawings has a frame including a horizontally disposed work-support comprising a bed-plate 10 provided with left and right slide-plates 11 and 12. Rising from one end of the bed-plate 10 is the hollow standard 13 of a bracket-arm 14 terminating at its free end in a head 15.

Extending longitudinally of and disposed within the bracket-arm 14 is a horizontally disposed rotary main or arm-shaft 16, one end of said shaft carrying a belt-pulley 17 and being journaled in a ball-bearing 18 disposed within a bearing-boss 19 projecting from the bracket-arm 14.

2

The main-shaft 16 is journaled in bearing bushings 20 and 21 and, at its end adjacent the bushing 21, carries a crank 22 connected by the usual link 23 with a needle-bar 24 carrying at its lower end a pair of needles 25 arranged abreast with respect to the direction of feed of the work.

The needle-bar 24 is journaled for vertical reciprocation in a pendulous frame 26 pivotally hung upon a fulcrum-pin 27 for swinging movements within the head 15 about an axis substantially parallel to the axis of rotation of the main-shaft 16.

For imparting swinging or work-feeding movements to the needles 25, there is provided an adjustable eccentric 28 on the shaft 16. Embracing this eccentric is a pitman 29 (see Fig. 6) to which is pivotally connected a crank 30, the lower end of which is made fast to a needle-feed rock-shaft 31 by means of the clamp 32 and clamp-screw 33. Rock-shaft 31 is journaled within apertures 34 and 35 provided in the wall-sections of the bracket-arm 14. At the forward end of the rock-shaft there is formed a bent crank-arm 36 operatively connected to the lower end of the pendulous frame 26 to impart vibratory movements thereto about the fulcrum-pin 27. This arrangement provides simple and well-balanced means for transmitting unison work-advancing and return movements to the needles 25. The usual eccentric-adjusting means 37 are provided on shaft 16 for adjusting the throw of eccentric 28 so as to vary the amplitude of the work-feeding movements of the needles 25. An adjustable eccentric of this type is fully disclosed in the U. S. patent to W. Myers, No. 2,128,031, August 23, 1938.

Disposed below and adjacent the rearward edge of the bed-plate 10, substantially parallel to the main-shaft 16, is a primary loop-taker and feed-actuating bed-shaft 38. Adjacent one end thereof, the shaft 38 is journaled in a bearing-bushing 39 sustained by a bearing-lug 40 depending from the bed-plate 10. Proximate to its opposite end, the shaft 38 is journaled in a bearing-bushing 41 secured in a lug 42 depending from the bed-plate 10. At its free end, adjacent to the bushing 39, the shaft carries a peripherally grooved belt-pulley 43 connected by a clip-belt 44 with a similar pulley 45, of the same size as said pulley 43 and carried by the main-shaft 16, whereby the shaft 38 is driven at the same speed as said main-shaft 16.

Mounted beneath the bed-plate 10, in coaxial relation with the shaft 38 is a loop-taker actuating shaft 46. Adjacent its end proximate to the shaft 38, the shaft 46 is journaled in a bearing-

bushing 47 which is secured within a depending lug 48, and the opposite end of the shaft 46 is journaled in a bearing-bushing 49, which is secured in a depending lug 50.

Carried by the shaft 46, between the bearing-bushings 47 and 49, are two spiral-gears 51 and 52 in driving engagement with spiral-gears 53 and 54, respectively, the gear ratios being such that the driven gears 53 and 54 are rotated at twice the speed of the driving gears 51 and 52. The driven gears 53 and 54, are carried by vertically disposed loop-taker shafts 55 and 56, respectively, said shafts being of similar construction and each carrying at its upper end the usual loop-taker elements 56' and 57' respectively, which elements are of the vertical axis rotary hook type.

The loop-taker shaft 55 is journaled in a right-hand loop-taker bracket 57, said bracket having at its rearward end a split bearing-boss 58 adjustably clamped upon the bushing 47 by a screw 59. At its forward end, the bracket 57 is provided with a foot 60 having an upper face secured by a screw 61 against a seat afforded by the horizontally flattened lower end of a lug 62 depending from the bed-plate 10. The bracket-securing screw 61 passes through a slot 63 provided in the foot 60, said slot being elongated in a direction to provide for adjustment of the bracket 57 toward and from the path of needle reciprocation.

The loop-taker shaft 56 is likewise journaled in a left-hand loop-taker bracket 64 having at its rearward end a split bearing-boss 65 adjustably clamped by a screw 66 upon the bushing 49. At its forward end, the bracket 64 is provided with a foot 67 having an elongated slot 68 entered by a screw 69 which secures the foot 67 against a horizontal seat formed by suitably recessing a lug 70 depending from the bed-plate 10.

For a more detailed description and disclosure of this loop-taker mechanism, reference may be had to the herein before mentioned Patent No. 2,128,031.

Shaft 46 is normally driven directly by shaft 38 through a coupling or overload release clutch 71 (Fig. 3) which will be described in detail hereafter. Thus, rotation of the belt-pulley 17 will actuate the gears 51 and 52 for the purpose of driving the loop-taker mechanism in the usual manner.

The work is intermittently advanced past the stitch-forming mechanism by a so-called compound feeding mechanism including a lower four-motion or drop-feed and a needle-feed. The usual feed-dog 72 is secured to and carried by a feed-bar 72' provided with a fork 73 engaging a feed-lift actuating eccentric 74 carried by the loop-taker actuating shaft 46, thereby to impart rising and falling movements to the feed-dog. The feed-dog 72 is provided with a pair of needle apertures 25'.

The front end of the feed-bar 72' is pivotally secured to the usual feed-rocker 75 which is carried and actuated by a feed-advance rock-shaft 76 journaled in frame lugs 77, 78 and 79 depending from the bed-plate 10. The feed-dog 72 is given its feed-advance and return movements by shaft 76 through the medium of the rocker 75.

The rocking movements are imparted to the feed-advance rock-shaft 76 by the rotary shaft 38 through the medium of a pitman rod 80. The rear end of this pitman rod embraces an adjustable eccentric 81 actuated by the shaft 38 and provided with eccentric-adjusting mechanism 82 similar to the adjusting mechanism of the arm-shaft 16. The forward end of the pitman 80 is

pivotedly secured to a depending crank arm 83 clamped upon the shaft 76 by means of a clamp-screw 84. Thus, rotation of shaft 38 will impart the usual rocking movements to shaft 76. The lower feed eccentric 81 and the upper or needle-feed eccentric 82 may be adjusted by their respective adjusting mechanisms 82 and 37 to the end that the needles 25 and the lower feed-dog have similar work-feeding amplitudes.

It is the purpose of the above noted overload release clutch 71 to provide means effective, in the event either of the rotary hooks becomes jammed, to disconnect the primary bed-shaft 38 from the shaft 46, whereby the lower four-motion feed continues to operate in unison with the needle-feed, thereby eliminating the possibility of the needles striking the feed-dog and breaking.

The clutch 71 comprises a driving dog having arms 85 and 86 projecting radially from a hub 87 which is mounted upon the forward end of shaft 38 by means of set-screws 88. The free end portions of the arms 85 and 86 extend, respectively, into slots 89 and 90 provided in the flanged periphery of a driven clutch-member 91 which is freely journaled upon the reduced end of a collar 92 secured in turn upon shaft 46 by means of screws 93. The shoulder 94 of the collar 92 and a clutch-setting disk 95, which is secured to shaft 46 by means of a set-screw 96, confine the clutch-member 91 in position and prevent any movement thereof longitudinally of the shaft 46.

The collar 92 has a recess 97 with outwardly diverging inclined sides formed in the periphery thereof for receiving normally a wedge-shaped projection 98 formed on a link 99 which is pivotally secured at one end by a screw 100 to the side face of the clutch-member 91. The other end of the link is pivotally connected to a second link 101 by means of a pin 102 rigidly carried by the link 101. The opposite end of the link 101 has rigidly secured thereon a second pin 103, to which is pivotally connected one end of an arcuate spring 104. The opposite end of the spring 104 is pivotally secured upon the side face of the clutch-member 91 by means of a screw 105. The arcuate spring 104 is provided, intermediate its ends, with a shoulder portion 106 which is adapted to engage the inner face of the circular flange 107 of the clutch-member 91, thereby to form a fulcrum point for the arcuate spring.

Referring to Fig. 4, the arcuate spring 104 and the links 101 and 99 are so proportioned that the projection 98 is normally spring biased into engagement with the recess 97, to the end that the clutch-member 91 and the collar 92 are locked together. Therefore, rotation of the shaft 38 will turn the driving dog which, through the medium of the clutch-member 91 and collar 92, will rotate the shaft 46.

To break the toggle, formed by links 99 and 101, and reestablish driving relation, a pawl 108 (see Fig. 4) is pivotally mounted upon the pin 102 of the toggle link 101. The pawl 108 is adapted to engage a shouldered recess 109 in the periphery of the collar 92. A light bow spring 110, which has one end thereof disposed within an aperture 111 formed in the arcuate spring 104, yieldingly holds the pawl 108 in contact with the collar 92 by having the bent end portion 112 of the spring 110 biased against the pawl.

Operation

The driving element or dog rotates the clutch-member 91 in the direction indicated by the ar-

row in Fig. 4. When an excessive load or torque is applied to the shaft 46 the wedge-shaped projection 98 is forced out of the recess 97 in the collar by the inclined wall of the recess, thereby straightening the toggle, as shown by dotted lines in Fig. 4. Preferably, sufficient momentum is given the toggle when it is straightened to cause a slight reverse bending thereof, which is limited by the projection 112 formed on the link 99. The effect of this slight reverse bending of the toggle is to move the wedge-shaped projection 98 on the link 99 to a position in which it is entirely out of contact with the collar 92, as shown in Fig. 4. When the wedge-shaped projection 98 is moved to a position out of contact with the collar 92, the spring-pressed pawl 108 is moved outwardly with the link 99, and the free end of the pawl rides freely over the periphery of the collar 92 in a counter-clockwise direction as long as the clutch-member 91 overruns the collar 92. It will be observed that the free end of the spring 104 acts inwardly and, therefore, tends to break the toggle both inwardly and outwardly. It will be obvious that the maximum force required to straighten the toggle is at the beginning of the straightening operation, diminishing as the pivot points approach alignment.

When it is desired to reestablish driving relation, the driving dog and clutch-member 91 are rotated in the reverse direction. To accomplish this action, the operator need only turn the wheel 17 by hand. When the shouldered recess 109 in the collar 92 engages the pawl 108 which is urged inwardly by the light spring 110, the pivotal point 102 of the toggle is pulled inwardly, breaking the toggle and thereby forcing the projection 98 on the link 99 into the wedge-shaped recess 97 in the collar 92.

In order to hold the collar 92 in a fixed position while resetting the toggle, the above noted clutch-setting wheel 95 is provided on the shaft 46 and it is held rigidly thereon by means of the set-screw 96. The periphery of the wheel 95 is formed with a plurality of evenly spaced slots 113 which are adapted to be entered by a spring retracted detent 114 carried in the bed-plate 10. By depressing the detent 114 against the force of the coil spring 115 to the extent that the detent enters one of the slots 113, the operator effectively locks the shaft 46 and collar 92. The overload release clutch 71 may then be readily reset as above described.

Thus it is to be understood that in the event either of the rotary hooks becomes jammed, the clutch 71 will disconnect shaft 46 from shaft 38, thereby to permit the lower and upper feeding mechanisms to operate in unison although the hook-actuating elements have ceased to operate.

Having thus set forth the nature of the invention, what I claim herein is:

1. In a sewing machine, in combination, a work-support, an endwise reciprocatory and laterally vibratory needle, a rotary loop-taker disposed below said work-support and complementary to said needle in the formation of lock-stitches, a rotary actuating shaft disposed below said work-support, work-feeding mechanism, actuating means carried by said rotary shaft for imparting work advancing movement to said work-feeding mechanism, a rotary loop-taker actuating shaft disposed below said work-support, and driving connections spaced from said feed actuating means and including an overload release clutch between said shafts.

2. In a sewing machine, in combination, a

work-support, stitch-forming mechanism including a thread-carrying needle and a rotary loop-taker, means for reciprocating said needle, a rotary actuating shaft disposed below said work-support, a work-advancing feed-dog operating through said work-support, actuating means carried by said rotary shaft for imparting work advancing movement to said feed-dog, a rotary loop-taker actuating shaft disposed below said work-support, driving connections spaced from said feed actuating means and including an overload release clutch between said shafts, and means for imparting work-advancing movements to said needle in unison with the work-advancing movements of said feed-dog.

3. In a sewing machine, in combination, a work-support, stitch-forming mechanism including a rotary loop-taker disposed below said work-support and an endwise reciprocatory and laterally vibratory needle, a work-advancing feed-dog operating through said work-support, a rotary actuating shaft disposed below said work-support and comprising aligned feed and loop-taker shaft-sections, means for rotating said feed shaft-section, actuating means carried by the feed shaft-section for imparting work-advancing movements to said feed-dog, driving connections spaced from said feed actuating means and comprising an overload release clutch between said shaft-sections, and operative connections with said loop-taker shaft-section for rotating said loop-taker.

4. In a sewing machine having a frame including a work-support and an overhanging bracket-arm, in combination, an arm-shaft rotatably journaled in said bracket-arm, a bed-shaft rotatably journaled at the under side of said work-support, driving connections for rotating said shafts in unison, a thread-carrying needle, operative connections with said arm-shaft for imparting endwise reciprocatory work-penetrating and laterally vibratory work-feeding movements to said needle, a feed-dog operating through said work-support, actuating means carried by said bed-shaft for imparting work-advancing movements to said feed-dog in timed relation with the work-feeding movements of said needle, a rotary loop-taker disposed below said work-support, a rotary loop-taker actuating shaft journaled below said work-support coaxially with said bed-shaft, driving connections spaced from said feed actuating means and comprising an overload release clutch between said bed-shaft and said loop-taker actuating shaft, and operative connections with said loop-taker actuating shaft for rotating said loop-taker a plurality of times for each reciprocation of said needle.

5. In a sewing machine having, in combination, a work-support, stitch-forming mechanism including a laterally vibratory and endwise reciprocatory thread-carrying needle and a rotary loop-taker, a rotary actuating shaft disposed below said work-support, means for rotating said shaft, work-feeding mechanism, actuating means carried by said rotary shaft for imparting work-advancing movement to said work-feeding mechanism, and a rotary loop-taker actuating shaft disposed below said work-support; the improvement which consists in the provision of an overload release clutch spaced from said feed actuating means and disposed in driving relation between said shafts, said clutch comprising, a rotatable driving element, a rotatable driven element, means for connecting said driving and driven elements, means for moving said connect-

ing means to an inactive position when a predetermined load is applied to said driven element, and a pawl under control of said driven element for thereafter moving said connecting means to its active position.

6. In a sewing machine having, in combination, a frame comprising a work-support and a bracket-arm over-hanging said work-support, a rotary needle-reciprocating shaft journaled in said bracket-arm, a rotary actuating shaft journaled below said work-support and disposed substantially parallel to said needle-reciprocating shaft, driving connections for rotating said shafts in one-to-one relation, an endwise reciprocatory and laterally vibratory needle-bar operatively connected to said needle-reciprocating shaft, a needle carried by said needle-bar, a loop-taker operatively connected to said actuating shaft to rotate a plurality of times for each needle reciprocation, a feed-advance rock-shaft journaled below said work-support and disposed substantially parallel to said actuating shaft, a work-advancing feed-dog operatively connected to said rock-shaft, and means carried by said actuating shaft for imparting oscillatory movement to said rock-shaft; the improvement which consists in the provision of an overload release clutch disposed in driving relation between said loop-taker and said actuating shaft and spaced from said rock-shaft actuating means, said clutch comprising, a rotatable driving element, a rotatable driven element, means for connecting said driving and driven elements, means for moving said connecting means to an inactive position when a predetermined load is applied to said driven element, and means under control of said driven element for thereafter moving said connecting means to its active position.

7. In a sewing machine, in combination, a work-support, an endwise reciprocatory and laterally vibratory needle, a rotary loop-taker disposed below said work-support and complementary to said needle in the formation of lock-stitches, a rotary actuating shaft disposed below said work-support, a rotary loop-taker actuating shaft disposed in alined relation with said rotary actuating shaft, driving connections including an overload release clutch between said shafts, work-feeding mechanism including a rock-shaft disposed in spaced parallel relation with said rotary actuating shaft, and driving means for said rock-shaft, said driving means being carried by said actuating shaft and spaced from said overload release clutch.

8. In a sewing machine, in combination, a work-support, an endwise reciprocatory and laterally vibratory needle, a rotary loop-taker disposed below said work-support and complementary

to the needle in the formation of lock-stitches, a work-advancing feed-dog operating through said work-support, a rotary actuating shaft disposed below said work-support, actuating means carried by said rotary actuating shaft for imparting work-advancing movement to said feed-dog, a loop-taker actuating shaft, driving connections spaced from said feed-advance actuating means including an overload release clutch between said rotary actuating shaft and said loop-taker actuating shaft, said clutch being adapted to disconnect said latter two shafts whenever a predetermined load is applied to said loop-taker actuating shaft, and means for reconnecting said latter two shafts through said clutch, said latter means including a manually controllable locking device associated with said loop-taker actuating shaft and adapted for locking said latter shaft against rotary movement.

9. In a sewing machine having a frame including a work-support and an overhanging bracket-arm, in combination, an arm-shaft rotatably journaled in said bracket-arm, a thread-carrying needle, operative connections with said arm-shaft for imparting endwise reciprocatory work-penetrating and laterally vibratory work-feeding movements to said needle, a bed-shaft rotatably journaled at the under side of said work-support, driving connections for rotating said shafts in unison, a rotary loop-taker disposed below said work-support and complementary to said needle in the formation of lock-stitches, a rotary loop-taker actuating shaft disposed in alined relation with said bed-shaft, driving connections including an overload release clutch between said bed-shaft and said rotary loop-taker actuating shaft, work-feeding mechanism disposed below said work-support, and actuating means spaced from said overload release clutch and carried by said bed-shaft for imparting work-advancing movements to said work-feeding mechanism in unison with the work-advancing movements of said needle.

HENRY C. NISSEN.
